UNITED STATES PATENT OFFICE.

WILBER KILLINGSWORTH, OF CHILlicothe, Ohio, ASSIGNOR TO THE CHILlicothe BEAN SNIPPER COMPANY, OF CHILlicothe, Ohio, A CORPORATION OF OHIO.

MACHINE FOR SNIPPING BEANS, &c.

1,246,110.

Specification of Letters Patent. Patented Nov. 13, 1917.

Application filed May 1, 1916. Serial No. 94,578.

To all whom it may concern:

Be it known that I, WILBER KILLINGSWORTH, a citizen of the United States, residing at Chillicothe, in the county of Ross and State of Ohio, have invented new and useful Improvements in Machines for Snipping Beans, &c., of which the following is a specification.

This invention relates more particularly to a machine for trimming or cutting off the opposite ends of string beans preparatory to canning or using the same for domestic purposes although this machine may also be used for trimming the ends of other articles.

In machines of this character, as heretofore constructed, the articles to be cut were placed in a plurality of pockets or buckets and successively presented to two sets of devices which successively operated on opposite ends of these articles, each of these sets comprising a gage or stop arranged adjacent to the path of the carrier at one end of the pockets, means for causing the articles in the pockets to be moved at one end against said gage, and a cutting device to which the articles were presented after reaching the gage and which operated to sever the respective ends of the articles.

While the articles were thus moved transversely in the pockets and presented to the respective gage and companion cutting device the same were confined within the pockets by means of a stationary cover extending across the upper side or open top of the pockets.

The purpose of the present invention is to improve the means for gaging the articles at their ends preparatory to cutting off those ends or tips of the articles where they have been gaged so as to avoid disturbing the position of the articles as they move from the gage to the cutting device and insure a more perfect and uniform severing of the ends of the articles, also to improve the means whereby the articles are moved transversely in the pockets toward said gage and cutting device, and also to improve the means whereby the tops or upper sides of the pockets are closed while the articles therein are presented to the transverse shifting means, the gage mechanism and the cutting mechanism.

In the accompanying drawings:

Figure 1 is a side elevation of a machine

for trimming the ends of articles which is constructed in accordance with my invention. Fig. 2 is a fragmentary longitudinal section thereof. Fig. 3 is a top plan view thereof with parts broken away. Fig. 4 is a fragmentary vertical longitudinal section, on an enlarged scale, taken on line 4—4, Fig. 3. Fig. 5 is a fragmentary vertical longitudinal section, on an enlarged scale, taken on line 5—5, Fig. 3. Fig. 6 is a rear end elevation of the machine. Fig. 7 is a fragmentary vertical cross section taken on the correspondingly numbered line in Fig. 3. Fig. 8 is a horizontal section taken on line 8—8, Fig. 4.

Similar characters of reference indicate corresponding parts throughout the several views.

The main frame of the machine may be of any suitable construction but as shown in the drawings the same comprises two upright longitudinal side walls or plates 1, 2 and upright legs or standards 3, 3, whereby these walls are supported on the floor. Between these walls is arranged the carrier whereby the articles to be cut or trimmed are presented to the gaging and cutting mechanism. This carrier or support may be of any suitable construction which will do the work but as shown in the drawings the same preferably comprises an endless belt 4 having an upper horizontal operative stretch and a lower horizontal inoperative stretch and passing with its front and rear turns around front and rear pulleys or wheels 5, 6. On its upper side this belt is provided with a plurality of transverse pockets, buckets or receptacles 7 which may be constructed of any suitable material and in any suitable form and each of which is open at its opposite ends and at its top or upper side. These front and rear supporting wheels are mounted on transverse shafts 8, 9 which are journaled in suitable bearings on the side walls of the main frame and power may be applied to this belt for moving the upper stretch forwardly or in the direction indicated by the arrow 10, the means for this purpose shown in the drawings consisting of a driving pulley 11 arranged on the shaft 9 of the rear supporting pulley and a driving belt 12 passing around the same. The articles to be trimmed at the ends, such for instance as string beans, are deposited in the pockets on the receiv-

ing part of the upper or operative stretch of the carrier adjacent to the front supporting pulley, this feeding of the articles being effected either by hand or by suitable 5 automatic mechanism so that they are arranged lengthwise in the several pockets. As the pockets loaded with the articles to be trimmed move forwardly they are first presented to a gaging mechanism arranged 10 on one side of the path of the carrier adjacent to the corresponding ends of the pockets and then moved transversely in these pockets so that one end of each of these articles engages the respective gage after 15 which those ends of the articles which have been gaged are presented to a cutting device which severs the respective ends of the article, and thereafter the articles are moved transversely in the pockets in the opposite 20 direction so that the other ends thereof are engaged with another gage arranged adjacent to the opposite side of the path of the carrier at the opposite ends of the pockets preparatory to being severed at the last mentioned gaged 25 ends by another cutting device. These two transverse propelling means, gaging means and cutting means which operate successively upon opposite ends of the articles form primary and secondary sets of devices 30 which operate successively on opposite ends of the articles and the construction of these two sets of devices is substantially alike. The essential features of the primary set of article treating devices are constructed as 35 follows:

13 represents a suction pipe arranged on one side, in this case the left side, of the main frame and provided at its upper end with a suction head or chamber 14 which 40 communicates with an opening 15 in the corresponding side walls of the frame horizontally in line with the path of one end of the pockets on the operative stretch of the carrier, while the opposite end of this suction pipe communicates with one side of the eye of the casing 16 of an exhaust fan arranged on the underside of the main frame. The blades of this fan may be turned in any suitable manner, for instance, as shown in 45 the drawings by means of a belt 17 passing around a pulley 18 on the main driving shaft 9 of the machine and a pulley 19 on the shaft 20 of the fan. As the pockets are successively presented at one 50 end to the mouth of the suction head 14 the movement of the air entering this head is in the direction crosswise of the pockets of the carrier and its pressure causes the articles 100 which have been deposited 55 in the same to be drawn transversely in one direction toward this suction head so that those ends of the articles which are at this time advancing under the action of this suction are caused to engage a gage 60 device, as shown by dotted lines in Fig. 8.

In its preferred form this gage device comprises a plurality of sets of gage disks or wheels 21, the members of each set being arranged in a vertical row and turning about the same axis, and the members of each set 70 being spaced apart and projecting into the spaces between the members of an adjacent set of such disks. As shown in the drawings three of such sets of gage disks are employed and arranged in a row lengthwise of the article carrier on one side thereof so that the inner faces of the several sets of gage disks form practically an even or uniform surface which is parallel with the direction of movement of the operative stretch of the carrier. The several sets of gage disks are arranged in the path of the current of air passing from the pockets into the suction head 14 and are turned so that the inner 80 sides of the several disks which face the open ends of adjacent pockets move forwardly or in the same direction as the pockets and at the same rate of speed. For this purpose the gage disks may be mounted in any suitable manner but in the preferred 90 construction which is shown in the drawings each set of these gage disks is mounted on an upright gage shaft 22 which is journaled at its upper and lower ends in suitable bearings formed on the upper and lower 95 sides of the respective suction head. The several gage shafts are caused to turn in unison by means of a horizontal driving shaft 23 journaled lengthwise in bearings on the upper side of the suction head and 100 operatively connected with the upper end of each gage shaft by means of a pair of intermeshing bevel gear wheels 24 the members of which are connected respectively with the horizontal shaft 23 and the upper 105 end of a gage shaft, as best shown in Fig. 4.

As the articles to be trimmed are drawn laterally outwardly with one of their ends against the inner surfaces of the gage disks the latter arrest this transverse movement 110 of the articles but do not retard the movement of the same lengthwise of the machine with the carrier inasmuch as the operative surfaces of the gage disk travel forwardly in the same direction as the carrier and at 115 the same rate, thereby avoiding displacement of the article preparatory to severing the gaged ends thereof. In order to enable the gage disks to aid in propelling the articles which are in contact with the inner surfaces of these disks the edge of each disk is preferably serrated or toothed, as shown at 120 25 in Fig. 8. These teeth enable each disk to obtain a better hold on the end of the article with which it engages and to positively 125 feed the same forward toward the cutting mechanism. After the articles have reached the gage device and have been gaged at one end thereof in the manner described the same are presented to a cutting device which 130

operates to snip off the gaged ends of the articles on a line between the gage and the adjacent ends of the carrier pockets.

In its preferred form this cutter mechanism, as best shown in Figs. 1-4 and 8, comprises a lower stationary cutter blade or knife 26 mounted on the adjacent longitudinal wall of the frame between the carrier and the primary gage disks, and an upper 10 rotatable cutter disk or knife 27 engaging with the outer side of the stationary cutter blade adjacent to the primary gage disks, the inlet of the pass between the stationary and movable cutter blades converging rearwardly and being arranged on a line with 15 the ends of the articles which project from the respective ends of the pockets of the carrier. The cutter disk 27 is mounted on a horizontal cutter shaft 28 which is journaled transversely in a bearing on the front 20 end of a vertically swinging rock arm 29. The latter is pivoted at its rear end on a transverse counter shaft 30 so that this arm and the cutter disk are free to rise and fall. 25 The downward movement of the cutter shaft may be limited by any suitable means, for instance by engaging the outer end of this shaft with a shoulder 31 on the adjacent part of the frame side wall, as shown in 30 Fig. 1. If an unduly hard article is presented by the pockets to the cutter mechanism its cutter disk will rise and clear such article but after the article has passed the upper cutter disk the latter again descends 35 by gravity into its normal position. The counter shaft 30 is journaled in suitable bearings on the upper part of the main frame and motion is transmitted from the same to the companion cutter shaft by means 40 of a belt 32 preferably of the chain type passing around sprocket wheels 33, 34 arranged on the counter shaft 30 and the inner end of the cutter shaft 28, as shown in Fig. 3.

45 In order to permit the length of snips which are cut off from the ends of articles to be accurately adjusted in accordance with the character of the material the gage mechanism is made adjustable toward and from 50 the path of such articles. Various means may be provided for this purpose but those shown in the drawings, and best shown in Figs. 4, 7 and 8, comprise adjusting bolts 35 passing through lugs 36 on opposite sides 55 of the suction head and having heads at their inner ends which bear against the inner side of the adjacent frame side wall and screw nuts 37 at their outer ends which bear against the lugs 36 and springs 38 interposed between the outer side of the adjacent frame side wall and the inner side of the lugs 36. Upon tightening the screw nuts 37 the gage disks are moved with the suction head toward the path of the articles which 60 are carried forward by the pockets, thereby

decreasing the length of the end portions of the articles which project laterally beyond the cutting line of the cutting mechanism. During such adjustment the springs 38 are compressed. Upon loosening the screw nuts 70 37 the springs 38 push the suction head outwardly and thereby carry the gage disks laterally away from the path of the articles to be trimmed so that a greater length of the end portions thereof projects laterally beyond 75 the cutting line of the blades and causes a proportionately longer snip to be cut off from such articles. After this adjustment of the gage mechanism is effected the same may be held securely in place by 80 means of a clamping bolt 39 passing through the lower part of the suction head and a slot 40 in the bracket 41 arranged on the adjacent frame side wall below the suction head.

85 After the articles in the pockets of the carrier have been cut or snipped off at one of their ends these articles during the continued forward movement of the carrier are presented to the secondary gage device which is arranged on the opposite side of the carrier adjacent to the path of the opposite ends of the pockets and the articles upon reaching this gage device are moved transversely in the pockets and drawn with their opposite ends against this secondary gaging 90 device by a secondary suction device. The latter is constructed substantially like the primary suction device and comprises a suction head 42 extending through an opening in the right hand frame wall so that the 100 mouth of this head is arranged in line with the opposite ends of the carrying pockets, and a suction pipe 43 connecting this suction head with the opposite side of the eye of the fan case so that when the machine is in operation a suction air current will be produced transversely across the pockets when they reach the mouth of the secondary suction head.

105 The secondary gaging device comprises 110 a plurality of sets of gaging disks 44, each set being arranged in an upright row but spaced apart and mounted on an upright gage shaft 45 which is journaled in suitable bearings on the companion suction head. 115 The gaging disks of each of the last mentioned sets are arranged between the spaces of the disks of an adjacent set and the several sets of these disks are arranged so that their inner sides practically form an even 120 or uniform gaging surface which is adapted to be engaged with the opposite ends of the articles which are to be trimmed. The inner or gaging sides of these disks move forwardly in the same direction as the pockets 125 at the same rate of speed for the purpose of avoiding displacement of the articles which are to be cut and also aiding in carrying the same forwardly to the secondary cutting device. This motion is preferably obtained 130

by the means which are shown in the drawings and which comprise a longitudinal driving shaft 46 journaled horizontally in suitable bearings on the upper part of the 5 secondary suction head and a plurality of pairs of beveled gears 47 the members of each pair being connected with the driving shaft 46 and the upper end of one of the gaging shafts 45. After the articles have 10 been thus drawn by the action of the air pressure with their opposite ends against the secondary gaging disks the articles during their continued forward movement with the carrier are presented to the secondary 15 cutting device which is constructed like the primary cutting device and comprises a lower stationary cutting blade or knife 48 arranged between the opposite ends of the pockets and the secondary gage device and 20 an upper movable cutter blade or knife 49 which preferably has the form of a disk and is also arranged between the opposite ends of the pockets of the secondary gaging device and coöperates with the lower sec- 25 ondary blade 48 so that the inlet of the pass between these blades converges forwardly and is in line with the path of the opposite ends of the articles to be trimmed, whereby the latter upon being moved forwardly by 30 the carrier have their opposite ends cut off. The amount of material which is cut off from the opposite ends of the articles may be determined by adjusting the secondary gage device laterally relatively to the sec- 35 ondary cutter, this being preferably accom- plished by means similar to those employed in connection with the primary gaging de- vice and comprising adjusting bolts 50 and 53 connecting lugs 51 on opposite sides of 40 the secondary suction head with the main frame, springs 52 interposed between these lugs and the adjacent part of the main frame, and a clamping bolt 54 connecting the underside of the secondary suction head 45 with a bracket 55 on the adjacent part of the main frame.

The two gaging devices are preferably caused to turn in unison by means of a trans- 50 verse shaft 99 journaled horizontally in suitable bearings on the main frame and pro- 55 vided at its opposite ends with two pairs of intermeshing bevel gear wheels 97, 98, one of which pairs connects the driving shaft 23 of the primary gaging device with this transverse shaft while the other pair con- 60 nects the driving shaft 46 of the secondary gaging device with this transverse shaft, as best shown in Figs. 1, 3 and 4. Although power may be applied to this gaging device 65 from any suitable source the means for this purpose which are shown in the drawings are suitable and comprise a short transverse shaft 57 journaled horizontally in suitable bearings on the secondary suction head, a pair of intermeshing bevel gear wheels 58

connecting this short transverse shaft with the rear end of the driving shaft of the secondary gaging device, and a belt 59 passing around pulleys 60, 56 on the main driving shaft 9 and the short transverse shaft 57, as 70 shown in Fig. 3.

The adjustment of the suction heads for the purpose of carrying the gage disks mounted thereon toward and from the companion cutting devices is comparatively 75 small and no serious interference with the driving mechanism of the gaging disks occurs inasmuch as there is sufficient looseness in the gears and sufficient spring in the longitudinal driving shafts of the gaging de- 80 vices to permit of such adjustment.

The secondary upper cutting disk is mounted on a short horizontal shaft 61 which is journaled transversely in a bearing arranged on the rear end of a vertically 85 swinging rock arm 62 which latter is piv- 90 otally mounted at its front end on the counter shaft 30, and motion is transmitted from this counter shaft to the secondary cutter shaft and the secondary upper blade by means of a belt 63 preferably of the chain type passing around driving and driven sprocket wheels 64, 65 secured respectively to the counter shaft 30 and the correspond- 95 ing ends of the cutter shaft 61.

The counter shaft 30 may be operated in any suitable manner, for instance by means of an intermediate shaft 66 journaled horizontally in suitable bearings on the main frame, a cross belt 67 passing around a pulley 68 at one end of the intermediate shaft and a pulley 69 on the corresponding end of the main driving shaft 9, and a straight belt 70 passing around a pulley 71 at the opposite end of the intermediate shaft and 105 a pulley 72 on the corresponding end of the counter shaft 30, as shown in Fig. 3.

In order to confine the suction of the ex- 110 haust fan to the pockets which for the time being are arranged transversely in line with the gaging devices and the cutting devices the tops or upper sides of the pockets are closed while passing the sucking, gaging and cutting devices and thereby insure exerting the full pressure of the air on the articles in the pockets so that they are prop- 115 erly moved with their ends against the gag- 120 ing devices preparatory to being operated upon by the cutting devices. The means for this purpose which are shown in the draw- 125 ings comprise an endless longitudinal cov- ering belt 73 having a lower operative horizontal stretch and an upper inopera- tive horizontal stretch, said lower stretch extending across the upper sides or tops 125 of the carrying pockets from a point in front of the primary suction, gaging and cutting devices to a point in rear of the secondary suction, gaging and cutting de- 130 vices. This covering belt passes with its

front and rear turns around front and rear pulleys 74, 75 which are mounted respectively on a transverse shaft 76 journaled horizontally on the adjacent upper part of 5 the main frame and the intermediate shaft 66 which forms part of the cutter driving mechanism. During the forward movement of the pockets past the suction, gaging and cutting devices the tops of the same are 10 closed by the lower stretch of the covering belt which latter moves in the same direction and at the same rate of speed, thereby confining the propelling effect of the air under pressure to the articles in the pockets 15 but preventing the articles from being crushed or caught between the cover belt and the pockets and also avoiding any waste of such material which otherwise would be liable to occur. In order to permit the air 20 to enter freely at the far ends of the pockets while the same is being exhausted therefrom at the near ends which are opposite the mouths of the suction heads, the main frame is provided with air inlet openings 25 77, 78 in the frame side walls adjacent to the far ends of the pockets transversely in line with the companion suction heads, as shown in Figs. 1, 7 and 8.

After the articles have passed the primary 30 and secondary cutting devices and both ends thereof have been trimmed off these articles are discharged from the pockets into a suitable receptacle or are otherwise disposed of as the pockets make the rear turn of the 35 carrier from the upper to the lower stretches thereof. The snips or pieces cut off from the ends of the articles are carried away from the outer sides of the cutting devices through the air conduits by the exhaust fan 40 and discharged by the latter to any suitable place.

This machine as a whole is comparatively 45 simple and inexpensive in construction considering the character of the work which it 50 performs. The same can be operated with a moderate amount of power, it is not liable to get out of order and the same is efficient in operation and capable of trimming articles such as string beans expeditiously 55 and economically with uniformity and practically no waste.

I claim as my invention:

1. A machine for trimming the ends of 55 articles comprising a support for the articles to be trimmed, a cutting device arranged adjacent to said support for trimming the articles thereon, and a fluid suction device operating to draw said articles on the support toward said cutting device.

2. A machine for trimming the ends of 60 articles comprising a support for the articles to be trimmed, a gage arranged adjacent to said support, a cutting device arranged between said gage and said support, 65 and means for drawing the articles by suc-

tion on said support against said gage preparatory to operating on said articles by said cutting device.

3. A machine for trimming the ends of 70 articles comprising a support for the articles to be trimmed, a gage arranged adjacent to said support, a cutting device arranged between said gage and said support, and means for drawing the articles by suc- 75 tion on said support against said gage preparatory to operating on said articles by said cutting device, said support being movable relatively to said gage and cutting device.

4. A machine for trimming the ends of 80 articles comprising a movable carrier adapted to support the articles to be trimmed, a gage for said articles comprising a rotatable disk having its edge facing said articles, and a cutting device to which said 85 articles are presented after reaching said gage.

5. A machine for trimming the ends of 90 articles comprising a movable carrier adapted to support the articles to be trimmed, a gage for said articles comprising a rotatable disk having its edge serrated and facing said articles, and a cutting device to which said articles are presented after 95 reaching said gage.

6. A machine for trimming the ends of 100 articles comprising a movable carrier adapted to support the articles to be trimmed, a gage for said articles comprising a rotatable disk having its edge arranged in the path of said articles and its operative side moving in the same direction as the adjacent part of the carrier, and a cutting device which operates on said articles after 105 the latter reach said gage.

7. A machine for trimming the ends of 110 articles comprising a movable carrier adapted to support the articles to be trimmed, a gage for said articles comprising a plurality of rotatable disks turning about the same axis and having their edges facing said articles, and a cutting device to which said articles are presented after reaching said gage.

8. A machine for trimming the ends of 115 articles comprising a movable carrier adapted to support the articles to be trimmed, a gage for said articles comprising a plurality of sets of disks, the members of each set turning about the same axis and arranged in the spaces between the disks of an adjacent set, and a cutting device to which said articles are presented after reaching said gage.

9. A machine for trimming the ends of 120 articles comprising a movable carrier adapted to support the articles to be trimmed, a gage for said articles comprising a plurality of sets of disks, the members of each set turning about the same axis and ar- 125

ranged in the spaces between the disks of an adjacent set, means for turning said several sets of disks in unison so that the sides thereof adjacent to said carrier move in the same direction, and a cutting device to which said articles are presented after reaching said gage.

10. A machine for trimming the ends of articles comprising a movable carrier adapted to support the articles to be trimmed, a gage for said articles comprising a plurality of sets of disks, the members of each set turning about the same axis and ar-

ranged in the spaces between the disks of an adjacent set, means for turning said 15 several sets of disks in unison so that the sides thereof adjacent to said carrier move in the same direction comprising a plurality of parallel gage shafts upon each of which one of said sets of disks is mounted, 20 a driving shaft arranged at right angles to said gage shafts and a pair of intermeshing bevel gear wheels connecting each gage shaft with said driving shaft.

WILBER KILLINGSWORTH.
